REINFORCED BUILDING CORNER

Sheldon F. Manning, South Bend, Ind., assignor
to Mastic Asphalt Corporation, South Bend,
Ind., a corporation of Indiana

Application May 1, 1939, Serial No. 271,043

12 Claims. (Cl. 20—5)

This invention relates to reinforced building corners, and particularly to building corners formed of rigid fibrous composition board.

The primary object of the invention is to provide a building corner formed of composition board and reinforced at both its front and back to prevent separation of the component sections of composition board.

A further object is to provide a building corner formed of composition board and reinforced by means positioned at its back and projected to the front of the corner.

A further object is to provide a composition board building corner having a metal reinforcing member constructed to compensate for expansion and contraction relative to the composition board.

A further object is to provide a building corner formed of composition board and having a rigid metal reinforcing member at its back and including projections extending through the composition board and overlying the front of the corner in a manner which does not interfere with adhesion of a surface coating to the board.

Other objects will be apparent from the description and appended claims.

In the drawing:

Fig. 1 is a front perspective view of the corner.

Fig. 2 is a transverse sectional view taken on line 2—2 of Fig. 1.

Fig. 3 is a perspective view of one of the reinforcing members illustrating the position of the other member in relation thereto by dotted lines.

Fig. 4 is a front elevation of the second reinforcing member.

Fig. 5 is a side elevation of the second reinforcing member.

Fig. 6 is a perspective view of a modified construction of the reinforcing member.

Fig. 7 is a perspective view of another modified construction of reinforcing member.

Referring to the drawing and particularly to Figs. 1 to 5 which illustrate the preferred embodiment of the invention, the numeral 10 designates the two angularly disposed panels of composition board constituting the corner. Panels 10 may be independently formed with meeting edges 11 thereof shaped at an angle of 45° to the panel faces; or said panels may be formed from a single sheet of composition board having a 90° V-shaped groove at the rear thereof and extending substantially through the board to permit the reduced thickness board portion at the apex of the groove to be bent. Suitable waterproofing adhesive is preferably applied at the meeting edges 11 of panels 10. The board comprising panels 10 is preferably surface saturated with asphalt or like waterproofing plastic to rigidify and strengthen the same.

The corner is provided with reinforcing means,

of which angle member 15, preferably formed of sheet metal, forms one part. Member 15 may be formed of transverse and longitudinal dimensions coinciding with the dimensions of the back of the corner, or may be either shorter or narrower than the corner. Where short sections are employed, the same are located at the ends of the corner unit, and may also be located intermediate the ends as desired or required. A plurality of thin elongated projecting fingers 16 are formed integrally with member 15 and project therefrom in spaced relation and are preferably longitudinally aligned in spaced relation to bend 17 of said member. Fingers 16 are preferably struck out from member 15, leaving spaced slots 18 in said member intermediate the side edges thereof. The leg or flange of member 15 opposite that from which fingers 16 extend is provided with a plurality of apertures 19 intermediate slots 18 and substantially vertically aligned with the ends of said slots.

A second reinforcing member comprises a metal plate 20 having a plurality of projecting fingers 21 struck out therefrom and extending perpendicularly thereto. Fingers 21 are spaced 25 apart and arranged to project through apertures 19 of member 15, and are of a small size to have free play in said aperture.

In assembling the corner, the member 15 is positioned in face contact with the back of the 30 panels 10, and fingers 16 thereof are passed through one of the boards at 25, either forcibly or through preformed passages in the board, in spaced relation to the meeting edges of the panel. Member 20 is then positioned against the leg of 35 member 15 having the apertures 19 to receive its fingers 21, and said fingers are also passed through the board adjacent thereto at 26. Fingers 16 and 21 are preferably of a length substantially greater than the thickness of board 10 40 so that the projecting ends thereof may be bent upon the outer faces of the panels 10 and preferably bent around the outer surface of the corner. The outer or end portions of the fingers are preferably pressed into the outer faces of the boards 45 to be flush therewith. This reinforces the corner at the outer surface thereof as illustrated in Figs. 1 and 2; and at the same time does not interfere with adhesion of surfacing material such as asphalt to the board, as illustrated in 50 dotted lines in Fig. 2. The members 15 and 20 not only hold panels 10 in operative relation to prevent separation thereof, but also serve to rigidify the resultant corner, to prevent deformity thereof, and to greatly increase the longitudinal strength of the corner. The fingers 16 and 21 are preferably of bent cross section to 55 strengthen them and assist in penetration of the board.

One of the salient features of this invention 60

resides in the use of two separate metal members to carry the sets of fingers passing through the opposite panels 10 forming the corner. The corner is intended to be used for an exterior 5 building covering and hence will be exposed directly to the weather. Metal reinforcements in installation of this character have heretofore been inoperative because metal has a substantially greater coefficient of expansion than the 10 composition board, and hence its constant exposure to the weather causes seasonal expansion and contraction tending to cause separation of the panel units and destruction of the seal and water-proofing thereof. This condition is successfully met in the instant construction by virtue of the fact that the fingers penetrating the opposite panels are carried by different metal parts, so that expansion of the metal parts 15 and 20 will not change the relative positions of panels 15 20. It will be observed in this connection that the slack fit of fingers 21 in apertures 19 insures against solid interconnection of the parts 15 and 20 in a manner to transmit expansive force therebetween. The construction has the further advantage of permitting the fingers 16 and 20 to tie the corner panels 10 together at their front faces so that the construction is reinforced at front and back and held against separation under all 25 conditions of expansion and contraction of the 30 plate parts 15, 20. Also, the parts 15, 20 constitute an effective longitudinal stiffening unit for the corner.

In geographical areas where temperature variations are not great so that expansion and contraction of metal is not a problem, it is possible to employ a simplified corner construction. Two 35 illustrative types of such a construction are shown in Figs. 6 and 7. In the Fig. 6 construction an angle reinforcement 30 of sheet metal or 40 other suitable material may have a plurality of fingers 31 struck out therefrom, which fingers 31 are of a length less than the thickness of composition board, but long enough to obtain a solid connection with the board when pressed therein. 45 In this construction the fingers are preferably of such transverse dimensions that they may be driven into the composition board. In the Fig. 7 construction the same general arrangement is employed as in Fig. 6, with the exception that 50 fingers 32 thereof are of a length corresponding generally to that of the fingers 16, 21 of the first mentioned embodiment, for passage completely through the composition board and extension to and beyond the corner at its outer face. For this 55 purpose the slots 33 formed in the angle member 30 incident to striking of the fingers 32 therefrom are necessarily so long that they extend into both flanges or legs of the angle member, necessitating staggering of the fingers 32 which project from the opposite legs or flanges of member 30. Both of these constructions serve to solidly 60 interconnect and reinforce the corner panels 10 and to increase the longitudinal strength and rigidity of the corner and also the resistance of 65 its construction to angular displacement of its panels.

I claim:

1. A reinforced building corner comprising two angularly disposed sections of composition board 70 having meeting edges, a metal angle member engaging the rear faces of said sections, one flange of said member having a plurality of projecting

fingers piercing one of said sections and the other flange having a plurality of openings formed therein, and a metal plate bearing against the last named flange of said angle member and having a plurality of projecting fingers extending through said apertures and piercing the other section. 5

2. The construction defined in claim 1, wherein all of said fingers are of a length greater than the thickness of said sections and their outer ends 10 are bent upon the outer faces of said sections and around said corner.

3. The construction defined in claim 1, wherein said last named fingers are of smaller transverse dimensions than said apertures to accommodate 15 relative movement of said angle member and plate incident to expansion and contraction thereof relative to said composition board sections.

4. The construction defined in claim 1 wherein 20 said fingers are struck out from said angle member and plate respectively to provide slots therein spaced from the edges of said members.

5. A reinforced building corner comprising two angularly disposed sections of composition board 25 in edge abutment, a pair of metal reinforcing members engaging said sections and each other, a set of fingers projecting from each member and into said sections, said members having a sliding interconnection to accommodate relative movement 30 thereof incident to expansion. 35

6. A construction as defined in claim 5 wherein said fingers are of a length to project through said sections with their outer ends bent to bear against the outer faces of said sections and extending into engagement with the section opposite that through which they pass. 40

7. A construction as defined in claim 5 wherein said fingers project through said sections with their free ends pressed into the outer faces of 45 said sections.

8. A construction as defined in claim 5 wherein said fingers project through said sections with their ends bearing against the outer faces of said sections and around the corner, the fingers of opposite members being arranged in staggered interdigital relation. 45

9. A construction as defined in claim 5 wherein one of said members is bent to reinforce both sections. 50

10. A reinforced building corner comprising two angularly disposed sections of composition board, a metal angle member engaging the rear sides of said sections, means carried by said member for piercing one section, a second metal member having a sliding interengagement with said first member, and means carried by said second metal member for piercing the other section. 55

11. A reinforced building corner comprising two angularly disposed sections of composition board, 60 metal reinforcing means engaging the rear sides of said sections, and projections carried by said means and projecting into both sections to interconnect said sections in operative position.

12. The construction defined in claim 11 where- 65 in said projections extend through said sections with their outer ends bent around the outer face of the corner, and a waterproof layer covering the outer faces of said section and the outer ends of said projections.
